WINDMILL TOY

Filed May 3, 1926

INVENTOR
Matteo De Cesare
BY
Warren E. Willis.
ATTORNEY

UNITED STATES PATENT OFFICE.

MATTEO DE CESARE, OF NEWARK, NEW JERSEY, ASSIGNOR, BY MESNE ASSIGNMENTS, TO METAL NOVELTY CORPORATION, OF NEWARK, NEW JERSEY, A CORPORATION OF NEW JERSEY.

WINDMILL TOY.

Application filed May 3, 1926. Serial No. 106,265.

This invention relates to miniature toy windmills and has as one of its objects to provide a device, the propeller shaft of which is freely mounted and rotatable in either direction.

Another object is in the provision of means, whereby an operator's hand coming in contact with the whirling propeller is unharmed.

10 A further aim is to provide a device capable of transmitting continuous motion in one direction without the necessity of intricate mechanical elements.

These and other objects, such as simplicity of construction, low cost of manufacture and ease of operation, are accomplished by the novel construction, combination and arrangement of parts, hereinafter described and illustrated in the accompanying drawings, forming a material part of this disclosure, and in which:—

Figure 1 is a front elevational view of an embodiment of the invention.

Figure 2 is a partial vertical sectional view taken on line 2—2 of Figure 1.

Figure 3 is a fragmentary vertical sectional view taken on line 3—3 of Figure 2.

In the drawing, the numeral 10 designates a rectangular hollow base having in 30 its upper surface openings 11 to engage lugs 12 formed on the lower extremity of a hollow conical body 13 illustrating a building, the same being held firmly together by lugs 14 engaging within mating apertures at the 35 abutting edges.

The upper end of the body 13 is arcuately cut as at 15 and integral therewith centrally located in the curves 15 are depending strips 16, the function of which will later become 40 apparent.

Projecting from the top of the body 13, at the front and rear thereof, are lugs 17 engaging openings 18 in the apex 19 of a V-shaped roof 20, the sides of which extend 45 downward to cover the arcuate portion 15.

Journalled in the body 13 is a spindle 21, at the front of which is mounted a thin metal spider 22 forming a plurality of arms 23 having projecting lugs 24.

50 The lugs 24 engage openings in light cardboard or wooden propellers 25, there being a collar 26 on the spindle 21, intermediate the body 13, and the propeller spider to allow for clearance of the body when the 55 propellers are revolved.

A second collar 27 is mounted on the spindle 21 within the body 13, adjacent the front wall to prevent the spindle from being removed from its position in the body 13.

Coiled twice about the spindle 21 as at 60 28 is a cord 29, one end of which is attached to a light circular weight or disc 30, the other end of the cord passing through an opening 31 in the side of the body 13, and terminating in a loop 32 to be grasped in 65 the fingers of an operator.

In operation the cord 29 is pulled downwardly intermittently, sufficient friction being caused by the double turn 28 of the 70 cord, to revolve the spindle 21, hence the propeller blades 25, the weight 30 acting to restore the cord to its normal position after each downward pull by the operator on the loop 32.

The weight 30 is prevented from rising too 75 high in the body 13 by the downwardly extending strips 16, thus removing the possibility of the weight being caught between the narrow upper portions of the body 13.

It will be noted that due to the looseness 80 of the coils about the spindle, the propeller veins may be revolved in either direction irrespective of the position of the cord or weight, thus eliminating the possibility of the device becoming out of order.

It is to be further noted the device is very simply assembled, there being no nuts, bolts or other complicated connections between the several parts.

The foregoing disclosure is to be regarded 90 as descriptive and illustrative only, and not as restrictive or limitative of the invention, of which obviously an embodiment may be constructed including many modifications without departing from the general scope 95 herein indicated and denoted in the appended claims.

Having thus described my invention, what I claim as new and desire to secure by Letters Patent, is:—

1. A toy windmill comprising a raised base, a hollow conical body mounted on said base, a V-shaped roof on said body, a spindle journalled in said body, a sheet metal spider fixed on said spindle, having opposed prongs at its ends, propeller blades secured by said prongs on said spider, a collar intermediate said body and said spider, a cord doubly coiled about said spindle, a weight at one end of said cord, 105 110

means formed on said body to limit the movement of said weight and a loop on said cord extending exteriorly of said body whereby said spindle is actuated.

- 5 2. A toy windmill comprising a base, a hollow body on said base, a roof on said body, a spindle journalled in said body, propeller blades mounted on said spindle, a cord coiled about said spindle, one end of said
- 10 cord passing through an opening in the wall

of said body to be grasped by an operator, a weight on the other end of said cord to return the same to its normal position during operation, and means integral with said body to prevent said weight from rising too ¹⁵ high within said body.

Signed at New York in the county of New York and State of New York this 30th day of April A. D. 1926.

MATTEO DE CESARE.
